(57) **CLAIM**

The ornamental design for a remote control for a toilet seat with bidet, as shown and described.

DESCRIPTION

FIG. 1 is a perspective view of a remote control for a toilet seat with bidet of the present invention;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a perspective view thereof showing the state in which the operating portion at the bottom is opened for showing portions of the design that are not shown in other views.
